(57) **CLAIM**

The ornamental design for a transfer robot, as shown and described.

DESCRIPTION

The patent or application file contains at least one drawing executed in color. Copies of this patent or patent application publication with color drawing(s) will be provided by the Office upon request and payment of the necessary fee.

1. Transfer robot

1.1 : Perspective view of a transfer robot

1.2 : Front

1.3 : Back

1.4 : Left

1.5 : Right

1.6 : Top

The transfer robot is used to pick and transfer material in warehousing scenarios; The bottom surface of the transfer robot is not easy to see or cannot be seen during use, so the bottom view of the transfer robot is omitted.

1 Claim, 6 Drawing Sheets
(6 of 6 Drawing Sheet(s) Filed in Color)
